United States Patent Office.

JOHN E. LAYTON, OF NEW WILMINGTON, PENNSYLVANIA.

Letters Patent No. 70,097, dated October 22, 1867.

IMPROVEMENT IN FENCE.

The Schedule referred to in these Letters Patent and making part of the same.

TO ALL WHOM IT MAY CONCERN:

Be it known that I, JOHN E. LAYTON, of New Wilmington, in the county of Lawrence, and State of Pennsylvania, have invented a new and useful Improvement in "Post-and-Rail Fence;" and I do hereby declare that the following is a full and exact description thereof, reference being had to the accompanying drawings, and to the letters of reference marked thereon.

The nature of my invention consists in providing the posts of the ordinary "rail fence" with supports, which are so arranged with relation to the posts and rails that the weight of the rails is brought to bear on the support in such manner that the weight of the rails will bear downwards in a straight line midway between the posts, thereby causing the posts to press towards each other in proportion to the weight of the rails.

My invention further consists in securing the posts to a base-piece by means of mortise and keys; the whole being constructed and operating in the manner hereinafter described.

To enable others skilled in the art of constructing fence to make and use my invention, I will proceed to describe its construction and operation. In the accompanying drawings which form part of my specification—

Figure 1 is a side elevation of my improved post-and-rail fence.

Figure 2 is an end elevation of the same.

In the drawings, A and B represent the posts, which are provided with a mortise in each, marked *o*. The posts are secured to the base, which consists of two pieces marked C and C', by means of keys 1 and 2. On the sides of the posts A and B are secured in an oblique position to the longitudinal plane of the posts the supports *e* and *i*, upon which rest the rails marked *g*. The supports *e* are secured to the post A, and the supports *i* are secured to the post B. The base-pieces C and C' rest on blocks or stones marked *x*.

The manner of constructing my improved fence will readily be seen and understood by the skillful mechanic by reference to the accompanying drawings, and the relation that the several parts bear to each other will also be understood without further description. The skillful mechanic will also see that by my mode of constructing a post-and-rail fence, the size and form of the several parts may be varied to suit the judgment and taste of the constructor, and that a cheap, durable, and firm post-and-rail fence can be constructed on the plan herein described and represented.

Having thus described the nature, construction, and operation of my improvement, what I claim as of my invention, is—

The posts A and B, provided with supports *e* and *i* for the rails *g*, said posts being secured to the base C C' by means of keys 1 and 2, the whole being constructed, arranged, and operating substantially as herein described and for the purpose set forth.

JOHN E. LAYTON.
